FIG. 23.

RECEIVED
UNITED STATES PATENT OFFICE.

STEPHEN A. HUNTLEY, OF ELKPOINT, SOUTH DAKOTA.

MAGAZINE-FIREARM.

SPECIFICATION forming part of Letters Patent No. 695,882, dated March 18, 1902.

Application filed February 2, 1900. Renewed August 15, 1901. Serial No. 72,084. (No model.)

To all whom it may concern:

Be it known that I, STEPHEN A. HUNTLEY, a citizen of the United States, residing at Elk-point, in the county of Union and State of South Dakota, have invented a new and useful Improvement in Firearms, of which the following is a specification.

My invention relates particularly to automatic repeating shotguns and rifles, though **10** not limited thereto.

My primary object is to provide improved recoil-started mechanism for automatically reloading the gun, provision being made therein against harmful and wearing movement of **15** the parts relatively to the receiver during the recoil.

In the form shown in the accompanying drawings the invention comprises a gun the receiver whereof is telescopically connected **20** with the stock and carries mechanism to reciprocate the breech-block during the forward movement of the barrel and receiver, the stock being provided with a device for actuating said mechanism and with a spring for **25** storing the receiver and barrel to their normal position.

Certain portions of the gun mechanism—notably the magazine shell-stop and the actuating device therefor—are fully shown and **30** claimed in my pending application, Serial No. 715,850, filed May 6, 1899, and therefore are not shown in detail in the accompanying drawings.

In the drawings, Figure 1 is a broken **35** central vertical longitudinal section showing the position of the parts after the receiver, barrel, and magazine have been carried back (together) by the recoil and partially restored to their former position by the restoring- **40** spring, the breech-block-operating crank having been given a partial revolution during the partial forward movement; Fig. 2, a bottom plan view of a two-part magazine; Fig. 3, a broken view, in side elevation, showing **45** a detail of the connection between the two parts of the magazine; Fig. 4, a transverse section on line 4 of Fig. 3; Fig. 5, a similar section at line 5 of Fig. 3; Figs. 6 and 7, similar sections at lines 6 and 7 of Fig. 2; Fig. 8, **50** a central vertical section showing the parts in position for firing; Figs. 9, 10, and 11, side,

top, and front end views of the breech-block and locking-bolt therefor; Figs. 12 and 13, sections on lines 12 and 13 of Fig. 8; Fig. 14, a section at line 14 of Fig. 9; Fig. 15, a detached view of the shell-carrier; Fig. 16, a view of one-half of the stock and a section of the receiver, exposing the mechanism; Fig. 17, a section at line 17 of Fig. 16; Figs. 18 and 19, sections at the corresponding lines of Fig. 16; Fig. 20, a detail of a ratchet-wheel; Fig. 21, an inner view of a fragment of one side of the stock, showing the means for limiting the movement of the receiver in the stock; Fig. 22, a section at line 22 of Fig. 21; Fig. 23, a section through the magazine in front of the fore-arm or fore-stock and looking at the front end of the latter; Fig. 24, (near Fig. 1,) a broken section at line 24 of Fig. 1, showing the ejector; and Fig. 25, a view of a modification of the trigger.

A represents a preferably metallic hollow stock; B, a receiver telescopically connected with the stock and provided with rear side extensions B'; C, a barrel rigidly joined to the receiver; D, a two-part magazine, the rear part of which is rigid with the receiver; D', a shell-follower; D², Fig. 2, a spring therefor; D³, the rear fixed portion of the magazine; D⁴, the front movable portion thereof pivotally connected to a ferrule or ring a by a pivotal screw a', passing through a plug a' at the front end of said movable portion; D⁵, a split double ring embracing the barrel and the front end of the part D³ and held in place by a screw **85** b and provided with a bayonet-slot b'; D⁶, a movable locking member on the magazine part D⁴ provided with a projection c for interlocking with the slot b' and provided with a slot c', which when the members D⁵ and D⁶ **90** are interlocked registers with a slot c² in the magazine to permit movement of a button c³ on the follower D', and serving to lock the same in a retracted position by engagement with a recess or bay c⁴ at the extreme outer **95** end of the slot c²; E, shells or cartridges; F, a shell-carrier; F', a carrier-elevating lever pivoted to the breech-frame by a pin d; F², a device for actuating said lever; G, an ejector; H, a reciprocating breech-block moving in **100** guide-slots e in the sides of the receiver; H', a locking-bolt for the breech-block, which at

forwards also a part of the connecting means between the breech-block and the reciprocating mechanism; H^2 , the firing-pin extending through the breech-block; H^3 , an actuating-spring for the firing-pin; I , a sear for holding the firing-pin retracted; I' , an actuating-lever pivotally connected to the receiver by a pin f and supplied with a downturned trigger-engaging rear end; I^2 , the trigger pivoted to the stock on a pin f' ; I^3 , a trigger-guard pivotally connected at its rear end by a screw f^2 to the stock; J , a fore-arm within which the magazine slides; J' , a rearward extension of the fore-arm, which forms also the bottom 15 of the receiver, with which it has tongue-and-groove connection, Fig. 12, and is pivotally joined by a pin f^3 to the front end of the trigger-guard; K , a link pivotally connected to the rear end of the locking-bolt and to the 20 front end of a connecting-rod K' ; K^2 , a carriage comprising a shaft and rollers, the latter moving between flanges g on the inner faces of the receiver side extensions B' ; K^3 , a crank connected with the rod K' and pivoted 25 to the extensions B' on bearings g' ; K^4 , a crank-operating pinion fixed to one of the journal-studs of the crank; K^5 , a gear for imparting motion to said pinion; K^6 , a shaft journalized in the extensions B' and bearing 30 the gear K^5 , fixedly secured thereon, a loosely-journalized rack-operated pinion K^7 , a fixedly-secured ratchet-wheel K^8 , and a pawl K^9 , pivoted to the pinion K^7 on a stud h and held in engagement with the ratchet-wheel 35 by a spring h' ; L , a rack meshing with the loose pinion K^7 and fixed to the inside of the stock, (the removed half, Fig. 16;) M , Figs. 17 and 21, receiver-extension guides fixed to the inner surfaces of the sides of 40 the stock; M' , a yoke or loop embracing the rear ends of the extensions B' and firmly secured thereto, the sides of the yoke affording lugs on said extensions to move in the guides M ; M^2 , a recoil-compressed restoring-45 spring confined between the rear end of the yoke M' and the rear end of the stock; P , a stationary buffer for the crank K^3 , and Q a spring-catch fixed to one of the side extensions B' and preventing rebounding of the 50 crank after the completion of a revolution.

The stock may be made in any suitable manner. I have shown it formed of sheet-steel in two longitudinal sections, internal lugs, Fig. 16, being provided for convenience in joining the sections. The guides M , Figs. 21 and 22, are of sheet metal, riveted to the stock and having guide-channels k for the sides of the yoke M' to move in. The guide shown in Fig. 21 is provided with a recess or 60 slot k' at an angle to and communicating with the guide-channel, and this slot receives a stop-block k^2 , which may be manipulated by a button k^3 , projecting through a slot k^4 in the stock to obstruct the front portion of its 65 adjacent guide-channel (after the yoke M' has moved back) to prevent the receiver from

moving forward when for any reason it is desired to hold it retracted. A spring-held tapered retaining-pin in the wall of the slot k' serves to engage a depression in the block 70 and hold it elevated till downward pressure is applied at the button. To the inside of the stock is also attached the buffer P , the latter being provided with a spring-held buffer-head P' , as clearly shown in Fig. 19. 75

The receiver is provided internally with the breech-block guide-grooves e mentioned, with vertical guide-grooves l for guide-lugs on the carrier, with depressed surfaces l' for carrier-depressing wings on the carrier, with a central groove l^2 for the upper extractor member, with inclined ribs or flanges l^3 , which limit the upward movement of shells being inserted or extracted, with a shoulder l^4 , with which the rear end of the locking-bolt engages, with a slot l^5 , Fig. 24, for the ejector, with a slot l^6 for the rear end of the trigger-engaging lever I' , with a spring l^7 for holding the sear I in engagement with the firing-pin, with relatively non-movable shell-stops l^8 , Figs. 1 and 12, with 80 a spring-held magazine shell-stop l^9 , (shown in dotted lines in Fig. 8,) and with guide-grooves l^{10} , Fig. 12, for engaging flanges on the rear extension of the fore-arm.

It will be understood that since the stock 95 stands still at discharge while the receiver moves back and down in virtually inclined guides the trigger-guard is swung downwardly somewhat about the pin f' , thereby forcing the fore-arm extension J' forward. 100 With the exception of the slight movement thus given to the fore-arm the latter remains stationary during the recoil, and so forms a practically immovable forward extension of the stock, affording a grip for the rest-hand. 105

The carrier F preferably has a rearwardly and downwardly inclined surface for the shell to lie in, is provided with guide-lugs m , which move in the grooves l of the receiver; with wings m' , having inclined rear edges for 110 engagement by the breech-block to be lowered thereby; with a spring-held lug m^2 for operating the magazine shell-stop, and with a groove m^3 in the upper surface of the bottom, with which the lower extractor member of 115 the breech-block engages to effect the initial lowering movement of the carrier.

The carrier-actuating lever F' is of bell-crank form and provided at its rear end with a gear-sector which engages with a gear-sector on the part F^2 . The part F^2 is pivoted in the receiver on a pin n and slotted to receive a pivoted pawl n' , which is caused to project at its rear end by a spring n^2 . In the rearward movement the breech-block slides 125 over the pawl n' ; but in the forward movement a shoulder at the pivoted end of the pawl is caused to engage the front wall of the slot in the part F^2 and rotate said part, thereby moving the carrier-actuating lever. 130

The breech-block is provided with a fixed lug p , on which the shell-flange rests, and a

spring-held movable member p^1 for catching upon the shell-flange. The lug p enters the slot m^2 of the shell-carrier during the forward movement of the breech-block and causes the initial depression of the carrier. The breech-block is further provided with an inclined perforation p^3 for the firing-pin, the main portion of which is of larger diameter than the front end to receive a spring-confining collar p^4 on the firing-pin and a spring-confining perforated plug p^5 , fixed to the breech-block by a pin p^6 . The firing-pin has a lower shoulder at p^6 for engaging the sear I and a lateral shoulder at p^7 for engagement with a safety catch or lug p^8 , (removed, but shown in dotted lines in Figs. 1 and 8 and shown in full lines in Fig. 12,) carried by the locking-bolt H'. The locking-bolt is of arched form and pivotally connected to the breech-block, being provided for the purpose with trunnion-like lugs p^9 , which fit into corresponding sockets in the breech-block. The breech-block is cut away back of its front end or head to receive the locking-bolt, as shown. The locking-bolt has a shoulder p^{10} for engaging the shoulder l^4 of the receiver. The lug p^8 has a rounded or beveled rear lower corner, so that its first effect when the locking-bolt is drawn down out of the locking position is to cause the firing-pin to move backward slightly and the lug p^8 to engage the shoulder p^7 on the firing-pin. The lug p^8 remains in the path of the shoulder p^7 until the breech-block has been reciprocated and re-closed, after which the locking-bolt is caused to swing upward to the locking position.

and the movable short arm (lug) at right angles thereto. A shoulder on the lug engages the rear wall of the slot q^4 , and a surface q^7 at an angle to the flat surface normally in engagement with the spring serves to restore the lug to its normal position after it has been sheathed in the slot q^4 during the forward movement of the breech-block. The rear ends of the (top and bottom) flanges of the piece q are provided with beveled surfaces q^8 , which engage corresponding beveled surfaces at the rear end of the slot l^5 , thereby rendering one securing-screw sufficient.

As shown in Fig. 23, the fore-arm J is of circular section and provided with an upper groove for the lower portion of the barrel. As the fore-arm is about ten inches in length in the ordinary shotgun, it is necessary to provide its front end with a slot r for the shell-follower button c^3 to move in, as shown in said figure. The button does not project quite flush with the surface of the fore-arm, whereby it is permitted to move beneath the hand. As shown in Fig. 8, the extension J' is provided at its front end with an integrally-formed magazine-encircling band r^2 , to which the fore-arm is secured by screws r^3 .

The operation is as follows: The magazine is filled by moving the shell-follower toward the muzzle by means of the button c^3 , locking said button in the recess c^4 , disengaging the connecting member D^4 and sliding it forward till it is wholly on the part D^4 , swinging the movable portion D^4 of said magazine on its pivot to expose the open end of the fixed part

Figs. 8, 11, and 12 show the breech-block provided with a slot p^{14} for receiving the pawl n' of the part F^2 , said slot being discontinued 40 a short distance to form a lug p^{12} for operating the part F^2 in one direction through the medium of its pawl. Fig. 12 shows the breech-block provided with guide-flanges p^{13} , and Figs. 9, 11, and 13 show a slot p^{14} for the 45 actuating-arm of the ejector, which runs through both breech-block and locking-bolt and turns downwardly at its rear end to permit said arm to enter as the locking-bolt swings downwardly. At its front end the slot 50 is discontinued to afford a lug p^{15} for moving said actuating-arm. Fig. 9 shows the front end of the breech-block provided with recesses p^{16} to prevent interference between breech-block and carrier and with shoulders 55 p^{17} for engaging the inclined surfaces of the wings m' of the carrier to depress the carrier.

The ejector, Fig. 24, comprises a fixed flanged slotted piece q , which fits in the slot b of the receiver, an arm q' , pivoted to said piece on a vertical pin q^2 , a lug q^3 , pivoted on the same pin in a slot q^4 in the arm q' , and a spring q^5 , secured to the piece q and to the receiver by a screw q^6 . The spring bears against the flat surface of a lug at the rear end of the arm q' and also against an adjacent flat surface of the lug q^3 , and thus serves to hold the long arm of the ejector sheathed

and the movable short arm (lug) at right-angles thereto. A shoulder on the lug engages the rear wall of the slot q^4 , and a surface q^7 at an angle to the flat surface normally in engagement with the spring serves to restore the lug to its normal position after it has been sheathed in the slot q^4 during the forward movement of the breech-block. The 75 rear ends of the (top and bottom) flanges of the piece q are provided with beveled surfaces q^8 , which engage corresponding beveled surfaces at the rear end of the slot l^5 , thereby rendering one securing-screw sufficient. 80

As shown in Fig. 23, the fore-arm J is of circular section and provided with an upper groove for the lower portion of the barrel. As the fore-arm is about ten inches in length 85 in the ordinary shotgun, it is necessary to provide its front end with a slot r for the shell-follower button c³ to move in, as shown in said figure. The button does not project quite flush with the surface of the fore-arm, 90 whereby it is permitted to move beneath the hand. As shown in Fig. 8, the extension J' is provided at its front end with an integrally-formed magazine-encircling band r², to which the fore-arm is secured by screws r³. 95

The operation is as follows: The magazine is filled by moving the shell-follower toward the muzzle by means of the button c^3 , locking said button in the recess c^4 , disengaging the connecting member D^6 and sliding it forward 100 till it is wholly on the part D^4 , swinging the movable portion D^4 of said magazine on its pivot to expose the open end of the fixed part D^3 , and finally inserting the shells into the part D^3 , then reconnecting the parts of the 105 magazine and releasing the button c^3 from the recess c^4 . The first shell may be introduced into the carrier by working the magazine shell-stop by hand. The barrel may then be charged by resting the stock against the body and pulling back on the barrel to set the spring M^2 . During this movement the pinion K^7 will run idly in its rack. In the return movement caused by the spring M^2 the pinion will, through the medium of its pawl 110 and the ratchet-wheel K^8 , revolve the shaft K^6 , gear K^5 , pinion K^4 , and crank K^3 , and thus positively reciprocate the breech-block, thereby setting the firing-pin and operating the ejector, carrier, and magazine shell-stop. At each 115

carries, and magazine shell-stop. At each discharge the recoil moves the barrel, magazine, receiver, breech-block, and reciprocating mechanism carried by the frame, back, compressing the spring M². The spring reacting restores these parts to their former position relatively to the stock, and during the restoring movement the rack in the stock actuates the reciprocating mechanism on the receiver. The movement of the breech-block extracts the shell, ejects it through a suitable opening (not shown) in the side of the receiver opposite the ejector, elevates the carrier, inserts a new shell, lowers the carrier, moves the magazine shell-stop to re-

charge the carrier, and sets the firing-pin against its spring ready for discharge. It is to be noted that when the receiver moves back the crank K³ is moved clear of the buffer 5 P and is thus left free to revolve during the forward movement. By the time the crank has completed a revolution it has been carried forward far enough to engage again the buffer. As the crank descends to its normal 10 position at rest it engages an inclined projection on the spring Q and moves the spring. The latter reacting causes the abrupt lower shoulder of the projection to engage and lock the crank, as shown in Fig. 19. The first 15 angular movement of the crank causes the link K to draw the locking-bolt H' out of engagement with the shoulder l¹ of the receiver and the lug p⁸ to engage the shoulder p⁵ of the firing-pin, as explained. As the breech-block moves back in its receiver the spring l forces the sear I into engagement with the shoulder p⁶ of the firing-pin. To permit 20 movement between the sear I and lever I', a pin-and-slot connection is used, as shown in 25 Fig. 8. During its movement the receiver slides over the upper end of the trigger, as more readily appears from Fig. 1.

In Fig. 25 I have shown a modified form of trigger with which it may be desirable to equip 30 certain firearms to prevent an involuntary second discharge of the weapon before the pressure of the finger can be removed from the trigger. In this form the upper portion of the trigger is made hollow to receive a spring-held 35 plunger x, which is provided with the upturned rear end for engaging the lever I'. The receiver is provided with an inclined groove x' to receive said upturned end, and a trigger-spring x² is provided for restoring the trigger 40 after the finger-pressure is removed. As the receiver moves forward after the recoil the upturned end of the part x enters the slot x' and is engaged by the downturned end of the lever I'. This compresses the spring of the 45 part x, and after the trigger has been released and moved by its spring the part x is forced out to properly engage the end of the lever I', as will be readily understood.

Various changes in details of construction 50 within the spirit of my invention may be made. For instance, the locking bolt or link H' when used should carry means for locking the breech-block; but it is not essential that this means be formed integrally with the part H'. 55 So the mechanism for reciprocating the breech-block may be varied; but it is important that the breech-block shall be positively actuated in both the opening and closing movement, as distinguished from the actuation (in opening) in one direction by the recoil. Preferably the entire reciprocation of the block occurs after the recoil and during the restoring movement. It is to be noted that the 60 distance of movement of the barrel, receiver, and breech-block under the recoil is only a fraction of the distance of movement of the breech-block through its reciprocating mechanism.

The breech-block is kept locked during the recoil, and no harmful separation of parts occurs, therefore, during the recoil. 70

The term "stock" as used in the appended claims is meant to cover any form of support for the barrel and receiver. In a broad sense the mechanism as a whole for positively moving the breech-block is recoil-started. In a 75 more limited sense such mechanism as is carried by the receiver and immediately connected with the breech-block is started by the device carried by the stock.

What I claim as new, and desire to secure 80 by Letters Patent, is—

1. In a firearm, the combination of a stock, a barrel, a receiver rigid with the barrel and movable on the stock, a breech-block in said receiver, mechanism carried by the receiver for reciprocating said block, a spring for restoring the receiver to its normal position, and rack-and-pinion connection between said stock and said mechanism, whereby said mechanism is caused to positively reciprocate 90 the breech-block during the movement of the receiver, substantially as and for the purpose set forth.

2. In a firearm, the combination of a stock, a barrel, a receiver rigid with the barrel and movable on the stock, a breech-block in said receiver, mechanism carried by the receiver for reciprocating said block, a spring for restoring the receiver to its normal position, a pinion connected with said mechanism and 100 carried by said receiver, and a rack fixed to said stock and engaging said pinion, substantially as and for the purpose set forth.

3. In a firearm, the combination of a stock, a barrel, a receiver rigid with the barrel and movable on the stock, a breech-block in said receiver for reciprocating said block, a spring for restoring the receiver to its normal position, an operating-pinion connected with said mechanism and carried by said receiver and running idly in one direction and operatively in 105 the other direction, and a rack fixed to said stock and engaging said pinion, substantially as and for the purpose set forth. 115

4. In a firearm, the combination of a barrel, a receiver rigid therewith provided with a rearward extension, a stock receiving said extension, a restoring spring between said receiver and stock, a reciprocable breech-block 120 in said receiver, a crank pivoted in said extension, connecting means between said crank and block, a pinion fixed to the axis of said crank to rotate therewith, and a rack fixed to said stock through the medium of which 125 rotary motion is imparted to the pinion, substantially as and for the purpose set forth.

5. In a firearm, the combination of a barrel, a receiver rigid therewith provided with a rearward extension, a stock receiving said extension, a restoring-spring between said receiver and stock, a reciprocable breech-block 130 in said receiver, a crank pivoted in said extension, connecting means between said

- crank and block, mechanism connected with stock and crank for actuating the crank, and a buffer in the stock for engaging said crank after each rotation, substantially as and for the purpose set forth.
6. In a firearm, the combination of a barrel, a receiver rigid therewith provided with a rearward extension, a stock receiving said extension, a restoring-spring between said receiver and stock, a reciprocable breech-block in said receiver, a crank pivoted in said extension, connecting means between said crank and block, mechanism connected with stock and crank for actuating the crank, a buffer in the stock for engaging said crank after each rotation, and a device for locking the crank against said buffer, substantially as and for the purpose set forth.
7. In a firearm, the combination of a barrel, a receiver rigid therewith provided with a rearward extension, a stock receiving said extension, a restoring-spring between said receiver and stock, a reciprocable breech-block in said receiver, a crank pivoted in said extension, connecting means between said crank and block, and hand-operated means projecting through the stock for engaging said receiver to lock it in the retracted position, substantially as and for the purpose set forth.
8. In a firearm, the combination of a stock, a trigger connected therewith, a barrel, a receiver rigid therewith and projecting into and movable in said stock, a reciprocating breech-block in said receiver, a firing-pin therein, an actuating-spring for said pin, a sear engaging said pin to hold it retracted, and a lever connected with said sear and pivoted in the receiver and contacting at its free end with said trigger in the firing position, substantially as and for the purpose set forth.
9. In a firearm, the combination with barrel, receiver, stock, and restoring-spring between receiver and stock, of a reciprocating breech-block in said receiver, a pivoted locking-bolt connected with said block and carrying means for engaging the receiver to lock the block, reciprocating mechanism, and connecting means between said mechanism and locking-bolt, which serves first to swing said locking-bolt and unlock said block, and then, through the medium of said locking-bolt, to reciprocate the block, substantially as and for the purpose set forth.
10. In a firearm, the combination with barrel, receiver, stock, and restoring-spring between receiver and stock, of a reciprocating breech-block in said receiver, a pivoted locking-bolt connected with said block and carrying means for engaging the receiver to lock the block, a firing-pin in said block provided with a shoulder, an actuating-spring for said pin, a lug on said locking-bolt for engaging said shoulder and locking said pin, reciprocating mechanism, and connecting means between said mechanism and locking-bolt, which serves to swing said locking-bolt and unlock said block, lock the firing-pin and reciprocate the block, substantially as and for the purpose set forth.
11. In a firearm, the combination with a receiver and reciprocating breech-block, of a shell-carrier, a carrier-actuating lever pivoted in the frame and having one end engaging said carrier and the other provided with a gear-sector, a pivoted sector F^2 engaging said first-named sector, and a movable catch between the breech-block and the sector F^2 operating during the forward movement of the breech-block to rotate said sector, substantially as and for the purpose set forth.
12. In a firearm, the combination with a receiver, of a pivoted ejector, a reciprocating breech-block provided with an ejector-arm groove, a locking-bolt pivotally connected to said block and provided with an ejector-arm groove, a stock telescopically receiving said receiver, and a restoring-spring between stock and receiver, substantially as and for the purpose set forth.
13. In a firearm, the combination with a receiver, a reciprocable breech-block therein provided with an ejector-engaging lug, and an ejector comprising an arm pivoted adjacent to its rear end on a vertical pivot and left free at its opposite end to engage a shell, a lug pivoted in a slot in said arm and projecting normally at right angles to said arm and having a shoulder engaging the rear wall of the slot in which it is pivoted, and a common spring fixed to the receiver and bearing upon said arm and lug and tending to hold the arm to the side of the receiver and the lug at right angles to the arm, substantially as and for the purpose set forth.
14. In a firearm, the combination with a receiver provided with an ejector-receiving slot, of a slotted ejector-arm frame in said slot and fixed to the receiver, an ejector-arm pivoted in said ejector-arm frame, and provided with a slot, a lug in the slot of said arm and on a common pivot with the arm, said lug being provided with a spring-engaging shoulder and with a shoulder for engaging the rear wall of the slot of said arm, and a spring secured to said ejector-arm and bearing against said arm and said lug and tending to keep the arm sheathed and the lug at right angles to the arm, substantially as and for the purpose set forth.
15. In a firearm, a stock, a barrel movably connected therewith, a restoring-spring in the stock, a forearm slidably connected to the barrel, and a rearward extension of said forearm connected with said stock, substantially as and for the purpose set forth.
16. In a firearm, a stock, a barrel movably connected therewith, a restoring-spring in the stock, a forearm slidably connected to the barrel, a rearward extension of said forearm, and a trigger-guard pivotally connected to stock and extension, substantially as and for the purpose set forth.

BEST AVAILABLE COPY

695,882

17. In a firearm the combination with a barrel and receiver, of a two-part magazine parallel to the barrel, comprising a fixed rear part, D³, a swinging part, D⁴, pivotally joined at its front end to the barrel by a pivot perpendicular to the barrel, a fixed locking-ring D⁵ on one of said magazine parts, and a mov-

able locking-ring D⁶ on the other of said magazine parts, substantially as and for the purpose set forth.

STEPHEN A. HUNTLEY.

In presence of—

D. W. LEE,

ALBERT BACCI.
